UNITED STATES PATENT OFFICE.

HAROLD L. LEAS, OF WAUKON, IOWA.

STARTER FOR INTERNAL-COMBUSTION ENGINES.

Application filed July 14, 1921. Serial No. 484,751.

This invention relates to starting devices for internal combustion engines, and more particularly to starters operated by compressed air or other gas.

5 An object of the invention is to provide a starter consisting of suitable valve mechanism timed with the engine and adapted to deliver a charge of air to the engine cylinder on one stroke and a charge of air and fuel 10 to said cylinder on another stroke.

A further object of the invention is the provision of means for relieving the compression in the other cylinders until an explosion is obtained.

15 In the present construction, the feed valve of the starter mechanism is adapted to open on the power stroke of the engine cylinder and deliver a charge of compressed air to the cylinder and throw the piston over. On 20 the inlet stroke, the air valve is again opened, and a second valve is opened, feeding a charge of fuel, in admixture with the air, to the engine cylinder.

The valves are operated by cams mounted 25 on a cam shaft and geared to a part of the engine to properly time the opening and closing of the valve. When the engine is started, the valves may be thrown out of operation, and the engine functions in its ordinary manner.

In the accompanying drawings, I have shown one embodiment of the invention. In this showing:

Figure 1 is a side elevation of an engine 35 showing the invention applied,

Figure 2 is a front elevation,

Figure 3 is a side elevation of the starter valve mechanism detached,

Figure 4 is a plan view,

40 Figure 5 is a transverse sectional view on line 5—5 of Figure 4,

Figure 6 is a horizontal sectional view on line 6—6 of Figure 5,

Figure 7 is a similar view on line 7—7 45 of Figure 5,

Figure 8 is a detail view of one of the shafts on which the valve rods are supported,

Figure 9 is a transverse sectional view on 50 line 9—9 of Figure 8,

Figure 10 is a detail perspective view of the valve actuating lever, and,

Figure 11 is a detail view of a pair of the fuel valves.

55 Referring to the drawings, the reference numeral 1 designates an internal combustion

engine, having the usual intake manifold 2, connected to the carburetor 3 by an intake pipe 4. A generator or magneto 5 is supported on the base of the engine, and connected to the main shaft by suitable gearing (not shown) to drive it when the engine is in operation. The generator is provided with a shaft 6 which, as shown, is extended rearwardly, the extension being supported in bearings 7. A gear wheel 8 is mounted on the shaft 6 and this gear meshes with a gear 9, mounted on the main cam shaft 10 of the starter mechanism. The gear 9 is adapted to mesh with a gear 11 mounted on the shaft of a pump 12, the pump shaft being provided with suitable clutch mechanism 13, whereby it may be thrown in and out, as desired. A pressure tank 14 is connected to the pump by means of a pipe 15, the tank being provided with a suitable gauge 16 to indicate the pressure therein. The tank is provided with an outlet pipe 17 in which a valve 18 may be arranged, if desired.

Referring to Figures 3 to 7 of the drawings, the starter valve mechanism comprises a housing 19, having bearings 20 arranged adjacent each end to support the cam shaft 10. The air pipe 17 is provided with a plurality of branches 21 connected to the inlet side of the housing and entering a plurality of chambers 22 arranged therein. The flow of air through these chambers is controlled by an inlet valve 23, engaging a valve seat in the inner wall of the chamber, the valve being mounted on a valve stem 24 and provided with suitable springs 25 to normally retain it in closed position. The valves 23 control communication between the chambers 22 and passages 26. As shown, in Figure 6 of the drawings, a plurality of passages 26 are provided, the number corresponding with the number of cylinders to the engine. The passages 26 are separated from each other by walls 27. A pipe 28 enters each of these passages, the pipes being connected to the cylinders of the engine, as shown in Figure 1.

A plurality of by-passes 29 communicate with the passages 26, the by-passes being open to the atmosphere at their other ends. Communication between the by-passes and the passages is controlled by exhaust valves 30 arranged on suitable valve seats and provided with stems 31. Springs 32 are arranged on the valve stems to normally retain

them in closed position. As shown, the exhaust valves are arranged on the opposite side of the housing from the inlet valves. Fuel valves 33 are arranged in suitable valve seats in the passages 26 on the opposite wall of the valve seats for the inlet valves 23. These valves are provided with stems 34, projecting in the same direction as the inlet valve stems and are normally retained in closed position by means of springs 35. Fuel valves are adapted to control communication between the passages 26 and fuel chambers 37. As shown, the fuel pipes 38 enter the fuel chambers 37.

15 The opening of the valves is controlled by means of rocker arms 39 which are mounted on shafts 40 arranged on each side of the cam shaft. As shown, the rocker shafts are supported in bearings formed in 20 the arms 41 of substantially U-shaped plates 42, secured to the side of the housing. Referring to Figures 8 and 9 of the drawings, the shafts are reduced in cross-section, at the points where the bearings are arranged 25 as illustrated at 43, and these reduced portions are arranged eccentric to the body portion of the shaft. When the rocker shafts are in operative position, shown in dotted lines in Figure 5 of the drawings, the inner ends 44 of the rocker arms are adapted 30 to engage suitable cams 45 on the cam shaft at proper intervals to swing the rocker arms and cause the other end 46 to engage the corresponding valve stem. The position of 35 the rocker shafts is controlled by means of hand levers 47 and 48, arranged on each of the shafts and provided with suitable connections (not shown) extending to the dash of the vehicle on which the engine is 40 mounted.

In operation, the pump 12 is connected to the drive mechanism through clutch 13 at suitable intervals when the engine is running to maintain proper pressure in the tank 45. The cam shaft 10 is driven at all times when the engine is running and the rocker shafts are normally arranged in the full line position whereby the rocker arms will not engage the cams 45. When the engine 50 is to be started, the levers 47 and 48 are moved to the dotted line position shown in Figure 5 of the drawings, to move the shafts 40 to the dotted line position shown in Figures 8 and 9, and position the rocker arms in engagement with the cams 45. The cam shaft is provided with cams adapted to open the inlet valve 23 of the starter mechanism of the cylinder that is about to start its power stroke. When the valve 23 is 55 opened, air flows through the pipes 17 and 21 to the chamber 22, thence to the passage 26 and to the cylinder by means of pipe 28. One of the cylinders will be on its compression stroke at this time, and the exhaust

60 valve 30 of this cylinder will be opened to relieve the compression in the cylinder and make it easier to drive the engine. The cylinder on its compression stroke will be placed in communication with the atmosphere through pipe 28, passage 26, valve 30, 70 and by-pass 29.

65 The momentum obtained during the power stroke of the cylinder to which the air is admitted will be sufficient to carry the piston through its exhaust stroke, and at the 75 beginning of the intake stroke, the valve 23 will again open and the fuel valve 33 will also open to permit the charge of fuel contained in the fuel chamber 37 to pass into the cylinder with the air. This highly atomized mixture of air and fuel will normally cause an explosion in the engine cylinder. The lever 48 is maintained in the dotted line position until the engine is started, thus relieving compression in each of the cylinders 80 during the starting operation. As soon as the explosion occurs in one of the cylinders, the lever is returned to the full line position and the valves 30 maintained in closed position. If the engine is cold and an explosion 85 is not obtained through a single operation of the starting mechanism, or if the engine does not continue running after the first explosion is obtained, the lever 47 is maintained in operative position until the engine 90 is properly started. The lever is then moved to the full line position, closing all of the valves of the starting mechanism, and the 95 engine functions in its normal manner.

100 It is to be understood that the form of my invention herewith shown and described is to be taken as a preferred example of the same, and that various changes in the shape, size, and arrangement of parts may be resorted to without departing from the spirit 105 of the invention or the scope of the subjoined claim.

Having thus described my invention, I claim:

110 A starter for internal combustion engines comprising a source of fluid pressure, connections between said source of fluid pressure and the cylinders of the engine, valves arranged in said connection to control the supply of air to the cylinders, an outlet 115 communicating with each of said connections, an exhaust valve arranged in said outlet, a fuel valve arranged in each of said connections, and control means for said valves to deliver air to the cylinder during one stroke, a mixture of air and fuel to the cylinder during another stroke, and to open 120 said exhaust valve during the compression stroke.

125 In testimony whereof I affix my signature.

HAROLD L. LEAS.
